DESIGN FOR A HAT

Sam Neger, New York, N. Y.

Application May 27, 1935, Serial No. 57,029

Term of patent 3½ years

To all whom it may concern:

Be it known that I, Sam Neger, a citizen of the United States, residing in Manhattan, in the city, county, and State of New York, have invented a new, original, and ornamental Design for Hats, of which the following is a specification reference being had to the accompanying drawing, forming a part thereof, in which

Fig. 1 illustrates a side perspective view of a hat showing my new design and

Fig. 2 is a plan view of Fig. 1.

I claim:

The ornamental design for a hat, substantially as shown.

Signed at New York, in the county of New York and State of New York this 25th day of May 1935
A. D.

SAM NEGER.
